UNITED STATES PATENT OFFICE.

GARLAND S. WILLS, OF TWIN BUTTES, ARIZONA.

WIRE-CONNECTOR.

1,106,855.

Specification of Letters Patent.

Patented Aug. 11, 1914.

Application filed September 14, 1912, Serial No. 720,393. Renewed September 24, 1913. Serial No. 791,650.

To all whom it may concern:

Be it known that I, GARLAND S. WILLS, a citizen of the United States, residing at Twin Buttes, in the county of Pima and State of Arizona, have invented certain new and useful Improvements in Wire-Connectors, of which the following is a specification, reference being had to the accompanying drawings.

10 This invention relates to connectors and more particularly to the class of wire connectors.

The principal object of the invention is the provision of a wire connector so constructed that the terminal ends of the wires may be effectively and readily secured within the connector against the accidental disconnection of the wires with the connector.

Another object of the invention is the provision of a connector so constructed that the wires may be repeatedly and effectively secured within the connector without the liability of injuring the wires.

Another object of the invention is the provision of a connector of the above stated character embodying clamps adapted to be forced into clamping engagement with the terminal ends of the wires arranged within the connector casing through the medium of 25 screw plugs threaded through the casing.

A still further object of the invention is the provision of a connector embodying clamps each adapted to be forced into clamping engagement with the wire terminals through the medium of a screw threaded through an opening in the split end of the connector casing, the diameter of the screw being slightly larger than that of the opening in the casing before the screw 35 is inserted therein whereby the binding action of the casing walls against the screw plug will be sufficient to produce a locking of the connector parts against relative movement.

40 With these and other objects in view as will appear as the description proceeds, the invention comprises the various novel features of construction, combination and arrangements of parts as will be more fully 45 described hereinafter and set forth with particularity in the appended claims.

Referring to the drawings Figure 1 is a sectional elevation of my improved wire connector; Fig. 2 is a top plan view thereof; 50 Fig. 3 is a vertical transverse sectional view taken on the line 3—3 of Fig. 1; Fig. 4 is a

fragmentary view of a portion of the connector casing with the screw plug removed therefrom; Fig. 5 is a sectional elevation of a modified form of wire connector, and Fig. 60 6 is a top plan view thereof.

Similar characters of reference are used to denote like parts throughout the accompanying drawings and the annexed specification.

65 Referring more particularly to the drawings, my improved wire connector is shown to consist of a tubular casing 1, the inner walls of which are depressed or bulged outwardly as shown at 2, at the opposite ends 70 of the casing. The upper portions of the casing are provided with threaded openings 3 in vertical alinement with the depressed portions 2, a boss 4 being formed upon the casing around each of said openings to reinforce them. The ends of the casing 1 are provided with longitudinal slots 5 which extend inwardly into communication with the threaded openings 3. A clamping member 6 is arranged for vertical movement in each 75 end of the casing. Each clamping member consists of a circular head 7 provided centrally upon its upper face with an upstanding stud 8, an upstanding arm 9 being formed at one side of the head 7 for vertical 80 movement within the slot 5 in the end of the casing 1. This arm 9 is of substantially rectangular cross-section so as to permit the clamping member to have a free vertical movement and yet prevent of its rotation or 85 lateral movement. The lower or active face of the clamping member 6 is concaved as shown at 10 so as to fit and overlie the terminal end of a wire disposed within the end of the connector casing. This active face 90 of the clamping member is also arcuately curved longitudinally, the end of the active face opposite to the upstanding arm 9 being disposed in a plane slightly below that of the other end.

100 Threaded into each of the openings 3 are screw plugs 11 and are provided in their under faces with vertically extending recesses 12 adapted to receive the studs 8 of the clamping members. By reference to 105 Fig. 4 it will be seen that the screw plug 11 is tapered at its lower end for about one-third of its length so as to permit of the plug being readily inserted and screwed into the openings 3 of the casing. It will also be 110 noted that the diameter of the screw plug above this tapered end is slightly greater

than that of the threaded opening 3. Now since the ends of the casing are slotted inwardly through the threaded openings 3, it will be apparent that as the plug 11 is 5 screwed into the opening 3 the walls of the opening 3 will be slightly expanded in receiving the screw plug. After the screw plug has been screwed down within the casing to an adjusted position it will be 10 obvious that the walls of the threaded openings 3 will tend to contract and assume their normal size or that size before the screw plug was inserted, thus producing a binding action between the plug and the walls of the 15 casing which will serve as a locking means to prevent the screw plugs from becoming loosened or disengaged from the casing. The upper face of the screw plugs 11 are provided with grooves 12 in which a suitable 20 instrument such as a screw driver may be inserted to screw the plugs down into the casing.

It is to be particularly noted from reference to Fig. 4 that the threads on the wall of 25 the opening 3 extend downwardly into the body or casing 1 and terminate on a line approximately coincident with the longitudinal axis of said casing. Opposite to this opening, the wall of the body or casing is 30 outwardly bulged or curved as above stated so that the plug 11 when threaded downwardly through the opening 3 clamps the wire against this curved casing wall and bends the same. The arc or curve of the 35 wire offers a greater contact surface with the casing wall than if the same extended in a straight line, thus materially increasing the electrical carrying capacity, by effecting a better contact between the wall and the 40 casing.

It is to be noted that in putting the invention into practical use, the clamping members 6 may be eliminated if desired, and the screw plug 11 alone relied upon to hold 45 the wire in connection with the casing. A strong and permanent connection is made possible by the relatively large number of threads provided upon the wall of the opening 3. In the ordinary devices of this character, only three or four threads are 50 provided so that the plug often works loose. By means of the present invention, all liability of the connector being destroyed by the formation of an arc which occurs when 55 the plug works loose, is obviated.

It will be apparent from the above construction that the screw plugs 11 are freely revoluble upon the studs 8 of the clamping members whereby the clamping members 60 may be forced downwardly into binding or clamping engagement with the terminal ends of a wire as the screw plugs 11 are screwed into the casing.

In Figs. 5 and 6 of the drawings, I have 65 illustrated a slightly modified form of the

invention wherein the casing 1 is provided adjacent its ends with the threaded openings 13 around which are formed the bosses or flanges 14 to strengthen the walls of the casing. Into each of these openings at one 70 side thereof, a rectangular recess 15 opens, the outer end of said recess being closed. A longitudinally extending slot or kerf 16 communicates with the closed end of this recess and allows of expansion of the metallic casing. The clamping member 17 which is of similar form to the corresponding member used in the main embodiment of the invention, is adapted to be inserted through the opening 13, the vertical arm of 80 said member fitting into the recess 15. The screw plug 18 is adapted to be threaded into the opening 13 and receives the stud of the clamping member as previously described, and by threading this member downwardly 85 through the opening in the casing, the clamping member 17 is forced downwardly into binding engagement with the terminal of the wire. The plug 18 is tapered slightly at its lower end as in the preferred form of 90 the invention.

From the foregoing description taken in connection with the accompanying drawings, the advantages of construction and the method of operation will be readily apparent to those skilled in the art to which the invention relates, and while I have described the principle of operation of the invention, together with the device which I now consider to be the best embodiment thereof, I 100 desire to have it understood that such changes may be made when desired as are within the scope of the appended claims.

Having thus fully described my invention what I claim as new is:

1. A wire connector comprising a tubular casing provided with a threaded opening and a longitudinal slot extending from one end of the casing into communication with the threaded opening, a clamping member 110 disposed within the casing for vertical movement and provided with an arm adapted to seat within the said slot, and a screw plug threaded into said opening and adapted to bear upon the clamping member. 115

2. A wire connector comprising a tubular casing provided with a threaded opening and a longitudinal slot extending from one end of the casing into communication with the threaded opening, a clamping member 120 disposed within the casing for vertical movement and provided with an arm adapted to seat within said slot, said clamping member being formed with an upstanding stud, and a screw plug threaded into said 125 opening and being provided in its lower end with a recess adapted to receive the upstanding stud on said clamping member, as and for the purpose set forth.

3. A wire connector comprising a tubular 130

casing provided with a threaded opening, and a longitudinal slot extending from one end of the casing into communication with the threaded opening, a clamping member 5 disposed within the casing for vertical movement and provided with an arm adapted to seat within said slot, a screw plug threaded into said opening and swivelly mounted upon said clamping member, said 10 plug having its lower end tapered for easy insertion of the plug into the opening, the largest diameter of said plug being greater than the normal diameter of the threaded opening within the casing, substantially as 15 and for the purpose set forth.

4. A wire connector comprising a tubular casing provided with a threaded opening and a longitudinal slot extending from one end of the casing into communication with 20 the threaded opening, the inner wall of said casing being bulged outwardly at a point in vertical alinement with the threaded opening therein, a clamping member disposed within the casing for vertical movement and provided with an arm adapted 25 to seat within said slot, a screw plug threaded into said opening and adapted to bear upon the clamping member, the lower face of said clamping member being curved to

conform to the curvature of the outwardly 30 bulged portion of the casing, substantially as and for the purpose set forth.

5. A wire connector comprising a tubular casing provided in one side with an opening and an outwardly projecting boss surrounding said opening, said boss being interiorly threaded, the walls of said casing upon opposite sides of said opening being also threaded and constituting a continuation of the threads of said boss, said latter threads 35 extending inwardly from the side walls of the casing to a point approximately coinciding with the longitudinal axis of said casing, and a threaded plug tapered at one end, the largest diameter of said plug being 40 greater than the normal diameter of the said opening, whereby in the insertion of the plug the casing walls are expanded and caused to bind against said plug to retain the same in position, said plug being of 45 appreciably less length than the length of the threaded portion of the casing.

In testimony whereof I hereunto affix my signature in the presence of two witnesses.
